TOOL FOR FORMING DETENTS IN CONNECTED CONVOLUTIONS OF SLATS

Frank J. Zarnowski, Rutherford, N. J., assignor to Orchard Brothers Incorporated, a corporation of New Jersey

Application April 29, 1954, Serial No. 426,374

6 Claims. (Cl. 164—121)

My invention relates to tools and more particularly to tools for operating upon awning slats which are marginally connected together.

One of the objects of my invention is to provide a tool equipped with means for operating on connecting convolutions of awning slats in a manner to provide the slats with anti-shifting means to preclude relative shifting of the slats lengthwise.

Another object of my invention is to provide a tool of the foregoing described character which may be readily applied to the slats for operation upon convolutions without modifying the slats for receiving the tool.

A further object of my invention is to provide a tool of the foregoing described character which functions in a manner to preclude marring or distortion of the slats other than providing the slats with anti-shifting means.

An important object of my invention is to provide a tool of the foregoing described character which is simple in construction, durable in use, efficient in operation, economical in manufacture and capable of utilization and operation by other than highly skilled labor.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a perspective view of a portion of an awning having my invention applied thereto.

Figure 2 is a side elevation of the tool.

Figure 3 is a detail longitudinal sectional view, on an enlarged scale, illustrating the convolutions of a pair of slats in position to be operated on by the tool.

Figure 4 is a view similar to Figure 3 but illustrating the convolutions formed with anti-shifting means as the result of the operation of the tool.

Figures 5 and 6 are detail sectional views taken on the lines 5—5 and 6—6 of Figure 4, respectively.

In practicing my invention, as illustrated in the drawings, I provide a tool of the plier type equipped with relatively movable handles 5 and 6 pivoted together by a pivot 7. The coincident ends of the handles 5 and 6 are connected to relatively movable jaw members 8 and 9 with the member 9 being formed with inner and outer, substantially parallel, spaced sections or walls 10 and 11, respectively, and defining therebetween a slot or channel. In order that the members 8 and 9 may be maintained in parallelism when operated to opened and closed positions by the handles, the intermediate portions of the members 8 and 9 are pivoted within the front ends of the handles by pivots 12 while their rear portions are pivotally and slidably connected within the handles by pins 13 fixed to the handles and extending through slots 14 in the rear ends of the members. The pivot 12 and the pin 13 for each member are equally distant from the pivot 7, whereby, parallelism of the members is maintained during relative movement of the members by the handles. Coil springs 15 are disposed within the handles

2

and have their front ends attached to the rear ends of the members 8 and 9 and their rear ends to the handles. When the jaw members are operated to closed position by gripping the handles and exerting pressure thereon, the springs 15 are extended and, when pressure upon the handles is relaxed, they contract and effect operation of the jaw members to open position as illustrated in Figures 1 and 2 of the drawings.

A cutting element or punch 16 has its operating end 17 operable into and out of a slot 18 formed in the section 10 of the jaw member 9. The other end of the punch 16 is threaded through the member 8 and is equipped with a lock-nut 19 engaging said member 8. By manipulating the nut 19, the punch 16 may be adjusted relative to the member 9. The operating end portion of the punch 16 is substantially rectangular in transversality while its operating end 17 is substantially cuneiform in side elevation, as clearly shown in Figures 3 and 4, to effect cutting and punching as hereinafter disclosed. The leading and trailing edges of the operating end 17 of the punch 16 are designated by the numerals 17a and 17b, respectively, in Fig. 3.

In order to provide an effective seat or retaining means for the connecting convolutions or hinges C of a pair of slats S of an awning A, for example, as disclosed in my copending application filed herewith, Serial No. 426,373, and enable proper functioning or operation of the tool in connection therewith, the confronting faces of the sections 10 and 11 are concave as at 20 to conform generally to the contour or curvature of the convolutions C inserted therebetween. When the members 8 and 9 are in open position, as illustrated in Figure 3, the operating end 17 of the punch 16 is maintained within the confines of the slot 18. However, when the members 8 and 9 are operated to closed position by the handles, the end 17 of the punch 16 is moved out of the slot 18 and cuts or punches the adjacent portions of the convolutions. As shown in Fig. 4, the punch 16 deforms the convolutions to form inwardly disposed detents D constituting anti-shifting means for the slats, as also disclosed in said copending application.

The degree of penetration of the punch 16 into the convolutions is limited by means of a stop 21 adjustably mounted on the member 8 and which stop engages the section 10 when the members 8 and 9 are operated to closed position to limit the movement of the punch 16. Support means for the portions of the convolutions adjacent the section 10 is provided and which comprises a pin 22 disposed between the sections 10 and 11. The pin 22 has an end portion extending through an opening formed in the end wall 24 connecting the sections 10 and 11 of the member 9 together. The pin is adjustably secured in the opening by means of a set-screw threaded in the wall 24. The opposite end portion of the pin 22 is conical and terminates in close proximity to but out of the path of the punch 16 when operated out of the slot 18 as clearly illustrated in Figure 4. When the tool is applied about the connecting convolutions C of a pair of the slats S, the pin 22 is disposed centrally within the confines of the convolutions to support the portions thereof adjacent the section and the conical end portion faces the path of the punch so as to cooperate with the leading edge of the end 17. As the latter engages the portions of the convolutions, distortion of the supported portions is precluded. The conical end of the pin serves to permit a slight inward deflection of the adjacent portions of the convolutions during severance to constitute additional detents D' as clearly illustrated in Figure 4.

From the foregoing, it will be apparent that I have provided an extremely simple and inexpensive form of tool for operating upon the hinges or convolutions connecting awning slats together to provide the slats with

means to prevent relative lengthwise shifting thereof. Furthermore, while I have disclosed my invention as being manually operated, it is to be understood that appropriate means may be employed for effecting power operation thereof. Also, it is comprehensible that the invention may be employed in connection with similar constructions other than the slats of awnings, for instance, panel assemblies for walls or the like wherein it is desirable to secure paneling against relative shifting.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In a tool construction, a member provided with spaced sections defining a channel therebetween for accommodating therein spaced pairs of connected portions of a pair of panels or the like and a slot opening into said channel through one of said section, a punch operable over a path extending through said slot and into said channel and having leading and trailing edges defining a work-face for penetrating and deforming one pair of said portions adjacent said slot to form detents therein to lock said panels together against relative shifting in one direction, a pin connected to said member and extending into said channel between and in spaced relation from said sections for supporting said one pair of said portions adjacent said slot, said pin terminating in proximity to but out of said path and coacting with said work-face to form detents in said one pair of said portions beyond said pin, said pin having a conical end section coacting with said leading edge to form detents in said one pair of said portions spaced from and opposite to said last mentioned detents, and stop means associated with said member and said punch for limiting the penetration of said punch to said one pair of said portions.

2. In a tool construction, a pair of relatively movable members with one of said members being provided with a pair of spaced sections for accommodating therebetween oppositely disposed spaced pairs of portions of connected convolutions of a pair of slats, one of said sections being formed with a slot, a punch connected to the other of said members and operable through said slot for penetrating the pair of said portions adjacent said slot to form detents in said last mentioned portions, and supporting means spaced from said sections in the zone between said sections and extending generally parallel to the adjacent faces of said sections so as to be disposed within the confines of said convolutions, said supporting means being disposed out of the path of said punch but with an end thereof close to said path for supporting said last mentioned portions and coacting with said punch to effect forming of said detents in said last mentioned portions.

3. In a tool construction, a pair of relatively movable members with one of said members being provided with a pair of spaced sections having confronting concave faces for accommodating therein the arcuate outer faces of oppositely disposed spaced pairs of portions of connected convolutions of a pair of slats, one of said sections being formed with a slot, a punch connected to the other of said members and operable through said slot for penetrating the pair of portions adjacent said slot to form detents in the last mentioned portions, supporting means

spaced from said sections in the zone between said sections and extending generally parallel to the adjacent faces of said sections so as to be disposed between said pairs of portions of said convolutions, said supporting means being disposed out of the path of said punch but with an end thereof close to said path for supporting the pair of portions adjacent said slot and coacting with said punch to effect forming of said detents in the last-mentioned portions, and a stop carried by one member for engaging the other member to limit the penetration of said punch to said last-mentioned portions.

4. In a tool construction, a member provided with a channel for accommodating therein spaced pairs of connected portions of a pair of panels or the like, said channel having a pair of substantially parallel walls and an end wall extending therebetween, said member having a slot opening into said channel through one of said parallel walls, a punch operable through said slot into said channel for penetrating and deforming a pair of said portions adjacent said slot to form detents therein to lock said panels together against relative shifting in one direction, and supporting means spaced from said parallel walls in said channel and extending from said end wall so as to be disposed between said pairs of portions, the end of said supporting means remote from said end wall being disposed close to said slot but out of the path of said punch.

5. In a tool construction, a member provided with a channel for accommodating therein spaced pairs of connected portions of a pair of panels or the like, said channel having a pair of substantially parallel walls and an end wall extending therebetween, said member having a slot opening into said channel through one of said parallel walls, a punch operable through said slot into said channel for penetrating and deforming a pair of said portions adjacent said slot to form detents therein to lock said panels together against relative shifting in one direction, and supporting means spaced from said parallel walls in said channel and extending from said end wall so as to be disposed between said pairs of portions, the end of said supporting means remote from said end wall being conical and being disposed close to said slot but out of the path of said punch.

6. In a tool construction, a pair of relatively movable members with one of said members being provided with a pair of spaced sections for accommodating therebetween oppositely disposed spaced pairs of portions of connected convolutions of a pair of slats, one of said sections being formed with a slot, a punch connected to the other of said members and operable through said slot for deforming the pair of said portions adjacent said slot to form detents in said last mentioned portions, and supporting means spaced from said sections in the zone between said sections and extending generally parallel to the adjacent faces of said sections so as to be disposed within the confines of said convolutions, said supporting means being disposed out of the path of said punch but with a portion thereof close to and facing said path for supporting said last mentioned portions and coacting with said punch to effect forming of said detents in said last mentioned portions.
